(57) CLAIM

The ornamental design for a ring, as shown and described.

DESCRIPTION

FIG. 1 is a front perspective view of a ring showing the new design;

FIG. 2 is a front view of the ring shown in FIG. 1;

FIG. 3 is a side view of the ring shown in FIG. 1;

FIG. 4 is a top view of the ring shown in FIG. 1;

FIG. 5 is a bottom view of the ring shown in FIG. 1;

FIG. 6 is a bottom perspective view of the ring shown in FIG. 1; and,

FIG. 7 is a bottom perspective view of a second embodiment of the ring shown in FIG. 1, the only difference being that the band portion includes no holes therein.

The broken line showing of the gemstones is for illustrative purposes only and form no part of the claimed design.
